COMBINED LAMP AND FLOWER HOLDER

Simon Wilson, 8103 S. Hooper Ave., Los Angeles, Calif.

Filed Dec. 5, 1963, Ser. No. 77,682

Term of patent 7 years

(Cl. D48—20)

The dominant features of my design reside in the portions shown in full lines.

I claim:

The ornamental design for a combined lamp and flower holder, substantially as shown and described.
